UNITED STATES PATENT OFFICE.

ROBERT F. FRAIZER, OF CLOVERDALE TOWNSHIP, PUTNAM COUNTY, INDIANA.

OVERSHOE-RETAINER.

No. 874,951.

Specification of Letters Patent.

Patented Dec. 31, 1907.

Application filed April 5, 1907. Serial No. 366,577.

To all whom it may concern:

Be it known that I, ROBERT F. FRAIZER, a citizen of the United States, residing in Cloverdale township, in the county of Putnam and State of Indiana, have invented 5 certain new and useful Improvements in Overshoe-Retainers, of which the following is a specification.

My invention relates to devices for supporting the heel portion of overshoes and 10 consists of a hooked bar to be secured to a shoe and a clamping member to be secured to the overshoe and adjustably secured to said hooked bar.

15 The construction and operation of my improved overshoe retainer will be described hereinafter and illustrated in the accompanying drawings in which—

Figure 1 is a view showing a shoe and an 20 overshoe with my improved retainer in position, Fig. 2, a front view of my improved device, Fig. 3, a side view, and Fig. 4, a detail view of the clamping member.

In the drawings similar reference characters indicate corresponding parts throughout 25 the several views.

My improved retainer for overshoes has a bar A having a hook B at its upper end to engage the top of the shoe 1 and a series of 30 holes C therein. Mounted on bar A is a clamping member D consisting of a base portion E having arms F at each side bent over the edges of bar A and forming the slides for adjusting the clamping member on said bar. 35 The arms F are then twisted so that their flat surfaces are parallel and are provided with holes G in their ends in which are pivotally secured the clamping tongue H. The other end of base portion E is formed 40 with prongs I, one at each side of bar A, and a lug or projection J to engage the holes C in said bar, said prongs I and lug J being at substantially right angles to base portion E.

K indicates a stop on the lower end of bar 45 A to limit the movement of clamping member D.

In use the hook B is secured over the top of the shoe 1. The overshoe 2 is then put on and the clamping member with the

clamping tongue H open is lowered so that 50 the prongs I engage the inside of the overshoe and the lug or projection J engages one of the holes C. The tongue H is then thrown into a clamping position and engaging the outside of the overshoe together 55 with the prongs I securely clamps the overshoe 2, while the lug J engaging one of the holes C prevents displacement of the overshoe.

The prongs I, as shown in Fig. 4, extend 60 over the edge of bar A so as to hold the end of the clamping member in position thereon.

Having thus described my invention what I claim is—

1. A retainer for overshoes comprising a 65 hooked bar having a series of holes therein, and a clamping member slidably mounted thereon having a lug to engage the holes in the bar, prongs extending upwardly from said clamping member to engage the sides of 70 said bar to hold one end of the clamping member on the bar and also to engage the inside of the overshoe, and a tongue pivotally secured to said clamping member to hold the overshoe in engagement with said 75 prongs, substantially as shown and described.

2. A retainer for overshoes comprising a hooked bar having a series of holes therein, and a clamping member slidably mounted 80 thereon consisting of a base portion, two arms extending from said base portion and bent over said bar to form slides, said arms being then twisted and extended on substantially parallel planes and provided with 85 holes in their ends, a clamping tongue pivotally mounted in the holes in said arms, a lug on said base portion to engage the holes in said bar, and prongs extending at right angles to said base portion, substantially as 90 shown and described.

In testimony whereof I hereto affix my signature in the presence of two witnesses.

ROBERT F. FRAIZER.
